A. U. G. BRANDON

VAPOR LAMP

Filed Dec. 10, 1926

Inventor:
Adele a George Brandon

Patented Feb. 15, 1927.

Des. 71,998

UNITED STATES PATENT OFFICE.

ADELE U. GEORGE BRANDON, OF NEW YORK, N. Y.

DESIGN FOR A VAPOR LAMP.

Application filed December 10, 1926. Serial No. 20,017. Term of patent 3½ years.

To all whom it may concern:

Be it known that I, ADELE U. GEORGE BRANDON, a subject of the Queen of Holland, residing at New York, in the borough of Manhattan and State of New York, have invented a new, original, and ornamental Design for Vapor Lamps, of which the following is a specification, reference being had to the accompanying drawing, forming part thereof.

The figure is a perspective view of a vapor lamp showing my new design.

I claim:

The ornamental design for a vapor lamp as shown.

ADELE U. GEORGE BRANDON.
